(57) **CLAIM**

I claim the ornamental design for a tube cleaning machine, as shown and described.

DESCRIPTION

FIG. 1 is a front elevation view of a tube cleaning machine, showing my new design;

FIG. 2 is a rear elevation view thereof;

FIG. 3 is a right side elevation view thereof;

FIG. 4 is a left side elevation view thereof;

FIG. 5 is a top view thereof; and,

FIG. 6 is a bottom view thereof.

1 Claim, 4 Drawing Sheets
